UNITED STATES PATENT OFFICE.

JOHN H. RIDENOUR, OF MUSKOGEE, OKLAHOMA.

SIGN-POST.

1,139,802.

Specification of Letters Patent. Patented May 18, 1915.

Application filed September 17, 1914. Serial No. 862,220.

To all whom it may concern:

Be it known that I, JOHN H. RIDENOUR, a citizen of the United States, residing at Muskogee, in the county of Muskogee and 5 State of Oklahoma, have invented certain new and useful Improvements in Sign-Posts, of which the following is a specification, reference being had to the accompanying drawings.

10 This invention relates to sign posts, and particularly to sign posts adapted for use at street corners to indicate the names of intersecting streets.

An object of this invention is the provision of a sign post of this character which is adapted to permanently support sign plates bearing the names of the intersecting streets, the post being also adapted to detachably support sign plates bearing advertising matter.

20 Another object of this invention is the provision of a sign post which is extremely simple in construction and which will be very efficient and durable in use.

25 With these and other objects in view, my invention consists in the novel construction, combination, and arrangement of parts, to be hereinafter more fully described, claimed, and illustrated in the accompanying drawing, in which—

30 Figure 1 is an elevational view of my improved post; Fig. 2 is a sectional view on the line 2—2 of Fig. 1; Fig. 3 is a fragmentary perspective view showing the manner of securing the advertising plates to the main sign plate; Fig. 4 is a top plan view; Fig. 5 is a sectional view of the lamp supporting means; and Fig. 6 is a fragmentary perspective view showing the manner in 40 which the opposing edges of the advertising plates are engaged against the wings of the post.

45 Referring more particularly to the drawing, the numeral 1 designates a base, of concrete or other similar plastic material, in which is formed a vertically angular recess 2. The post 3 is constructed of an angle bar which is formed with a pair of right angularly extending wings 4, the lower end of the 50 post being adapted for engagement in the

recess 2 in the base, whereby the post is supported in a perpendicular position. Rigidly secured to the upper end of the post by rivets or the like, is an angular sign plate 5 which consists of a pair of right angularly 55 extending portions 6, the portions 6 at their juncture being engaged against the outer faces of the wings 4 of the post. The sign plate 5 is adapted to bear on the opposite faces of its angularly extending portions, 60 the names of the streets with which the portions 6 extend longitudinally and to strengthen the portion 6 and prevent the same from bending, laterally extending flanges 7 are formed on their upper edges. 65

Secured to the inner face of each portion 6 at its lower edge is a longitudinal supporting strip 8, one edge of the strips projecting below the lower edge of the portions, and formed in the projecting portions of the 70 strips are a plurality of openings. Adapted for detachable connection to the strips 8 are advertising sign plates 9 in the upper edges of which openings are formed to register with the openings in the strips 8, the registering openings receiving the fastening bolts 10 whereby the advertising plates 9 are carried by the sign plate 4 with their inner edges engaged against the outer face of the wings of the post. To further support the 80 plates 9 in position, openings are formed in each of the wings which register with openings formed in the plates, the latter registering openings also receiving fastening bolts 10. Secured to the upper face of the meeting ends of the flanges 7 is a plate 11 which is provided with an upstanding stem 12, the stem being adapted to support a lamp, which will illuminate the signs at night. 85

90 From the above description taken in connection with the accompanying drawing, it will be seen that I have provided a sign post to which a street indicating sign may be permanently connected, the street indicating sign carrying means whereby advertising 95 sign plates may be detachably connected thereto so that the advertising plates may be changed at intervals. By providing the flanges 7 on the upper edges of the angularly extending portions of the sign plate 5, an 100

illuminating lamp may also be carried by the post so that the signs may be visible during the day and night.

Having thus fully described my invention, what I desire to claim and secure by Letters Patent is:

A device of the character described comprising an angular post, an angular sign plate secured to the upper end of the post, strips secured to the lower edges of the an-

gularly extending portions of the plate, said strips projecting below the lower edge of said plate, and sign plates detachably connected to said strips.

In testimony whereof I hereunto affix my 15
signature in the presence of two witnesses.

JOHN H. RIDENOUR.
